CLAIM

The new and ornamental design in a towel dispensing carton therefor, as shown and described.

DESCRIPTION

FIG. 1 is a plan view of a towel dispensing carton, in an unfolded condition, showing our new design; FIG. 2 is a top plan view of the article in the assembled condition;

FIG. 3 is a rear elevational view thereof;

FIG. 4 is a bottom plan view thereof;

FIG. 5 is a left side elevational view thereof;

FIG. 6 is a right side elevational view thereof;

FIG. 7 is a first elevated view thereof; and,

FIG. 8 is an isometric view thereof.

The dashed lines in FIG. 1 represent fold lines and the solid lines, except on the margin of the blank, represent cut lines in the blank.

FIG. I

FIG. 5
